UNITED STATES PATENT OFFICE.

SYLVESTER HENRY HUNT, OF NORFOLK, VIRGINIA, ASSIGNOR TO FARMERS MANUFACTURING COMPANY, OF NORFOLK, VIRGINIA, A CORPORATION OF VIRGINIA.

HAMPER HANDLE.

Application filed April 9, 1927. Serial No. 182,377.

This invention relates to that type of hamper or basket handle which serves in addition to its function as a handle to fasten the cover in place, and the object of this invention is to provide a simple device which will effectually hold the cover in place and serve, when the cover is detached, as a sturdy handle for the basket, as more fully hereinafter set forth.

10 In the drawing—

Fig. 1 is a perspective view of a portion of a basket showing my invention applied thereto;

15 Fig. 2 is a vertical sectional view on the line 2—2 of Fig. 1.

Referring to the annexed drawing by reference-characters, 5 designates the usual stave or splint wall of the basket, whose upper edge is clamped between a pair of hoops 6 by nails in the usual manner. The cover is likewise constructed in the usual manner in that it includes a hoop 7 and slats 8 fastened to the top edge of the hoop 7, one of the slats extending beyond the hoop to engage the handle.

20 The handle is constructed of a single piece of wire bent to form the handle-loop 9 (which rests upon the top edge of the slat 8) and two depending legs which are permanently attached to the body hoop 6. These legs each consist of a straight depending part 10, an inwardly-extending part 11 which lies upon the top edge of the double hoop 6, a depending part 12 lying against the inner face of the inner one of the hoops 6, an outwardly-extending part 13 which extends through the two hoops and the intermediate stave, and a terminal part 14 which extends upwardly and lies against the outer

face of the outer hoop 6, this upwardly-extending end terminating near the juncture of the parts 10 and 11. The end parts 14 are clamped hard against the outer face of the outer hoop so as thus to bind the intermediate parts of the hoops and the staves in 45 a strong loop formed by the parts 11, 12, 13 and 14. By having the terminal parts 14 on the outside, I avoid the danger of this end-portion bruising the fruit or vegetables packed in the hamper. The parts 11, lying 50 upon the top edges of the body hoops, afford a solid bearing for the cover-hoop 7 when the same is clamped down by the slat 8 being inserted under the handle-loop 9.

It will be understood, of course, that, as 55 usual, one of these wire handles will be arranged at the other side of the hamper.

What I claim as new is:

In combination with a basket having a hoop structure at its rim embodying two 60 hoops clamped upon the intermediate staves, and a cover embodying a hoop and a slat having its end extended, a combined cover-fastener-and-handle consisting of a handle-loop adapted to engage over the extended 65 slat and two depending legs each of which bends inwardly to lie upon the upper edge of the hoop structure, then downwardly to lie against the inner face of the inner hoop structure, then outwardly through the two 70 hoops and intermediate staves and finally upwardly to lie against the outer face of the outer hoop, the hoop structure being solidly clamped in the loop thus formed in each leg.

In testimony whereof I hereunto affix my 75 signature.

SYLVESTER HENRY HUNT.
